JOSEPH D. GALLAGHER, OF GLEN RIDGE, AND GEORGE COOK, OF ALLENDALE, NEW JERSEY, ASSIGNORS TO AMERICAN BRAKE SHOE & FOUNDRY COMPANY, OF MAHWAH, NEW JERSEY, A CORPORATION OF NEW JERSEY.

SEGMENTAL BRAKE-SHOE.

1,174,561.

Specification of Letters Patent.

Patented Mar. 7, 1916.

Application filed October 23, 1914. Serial No. 868,196.

To all whom it may concern:

Be it known that we, JOSEPH D. GALLAGHER, a citizen of the United States, and a resident of Glen Ridge, county of Essex, 5 and State of New Jersey, and GEORGE COOK, a citizen of the United States, and a resident of Allendale, county of Bergen, and State of New Jersey, have made and invented certain new and useful Improvements in Segmental Brake-Shoes, of which the following is a specification.

Our invention relates to an improvement in brake shoes for use upon railroad cars, and like vehicles, and more particularly to 15 that type or form which we term a "segmental" shoe, that is, a shoe wherein the body or wearing portion is provided with a plurality of slots, recesses or grooves extending inward from the wearing face substantially to the reinforcement on the back, and disposed on either side of the transverse 20 center of the shoe to divide it into a plurality of segments spaced apart.

In an application filed by one of the undersigned, Joseph D. Gallagher, on the 2nd day of May, 1913, and which application bears Serial Number 765,010, and which resulted in Patent Number 1,123,583, dated Dec. 29, 1914, there has been described a 25 shoe constructed in this way, that is, with a plurality of slots across the body of the shoe, the purpose being to prevent the warping, twisting or distortion of the same due to the fact that a solid shoe contains such a 30 quantity of metal that when applied to the tread of the wheel, the heat, generated by friction, tends to straighten out the body, thereby resulting in imperfect contact between the shoe and the tread of the wheel. 35 The shoe, being subsequently cooled, assumes a slightly different curve to that which it originally had, so that when again applied to the tread of the wheel, it contacts with the latter at the ends or toes of the shoe. 40 Only, the wearing portions or areas of the shoe thus constantly shifting from time to time as the shoe is heated up and subsequently cooled. It appears, however, that 45 in handling this slotted or segmental shoe, that is, in loading and unloading the same into and from the freight cars, and also during transportation, and also while being finished in the tumbling barrels, there is more or less danger of injuring the shoe by

cracking the metal adjacent to the reinforcing back, due to the fact that the slotting of the shoe partway through the body and to points in proximity to the reinforcing back or plate, permits it to be unduly straightened out, the cracks extending from the ends of the slots to the reinforcing plate. 55

The object of our present invention is to overcome this defect by tying or bonding together the free ends of the segments or sections constituting the body, thus preventing the distortion of the shoe above referred to. 65

A further object of the invention is to employ such means for tying or bonding the sections as above described as will be quickly 70 worn away when the shoe is put into service, allowing all the advantages inherent in a segmental shoe to be utilized and availed of after a few applications of the shoe to the tread of the wheel. 75

With these and other ends in view, the invention consists in certain novel features of construction and combinations of parts as will be hereinafter fully described and pointed out in the claim. 80

In the accompanying drawings, Figure 1 is a perspective view of a segmental shoe constructed in accordance with our invention. Fig. 2 is a sectional view taken on the line 2—2 of Fig. 1. Fig. 3 is a sectional view taken on the line 3—3 of Fig. 2, looking in the direction as indicated by the arrow. Fig. 4 is a perspective view of a modified form of the shoe. Fig. 5 is a sectional view taken on the line 5—5 of Fig. 4, looking in the direction as indicated by the arrow. Fig. 6 is a detached view in perspective of one of the devices illustrated in Figs. 4 and 5 for bonding the segments together. Fig. 7 is a view in perspective of a similar 95 shoe showing a modified form of the tie or bond. Fig. 8 is a sectional view taken on the line 8—8 of Fig. 7, looking in the direction as indicated by the arrow. Fig. 9 is a detached perspective view of the tie or bond 100 employed in the shoes illustrated in Figs. 7 and 8.

Referring to the drawings, 10 represents the body of a brake shoe ordinarily made of cast iron and provided with a key lug 11 about the center of its length for attachment to a brake head (not shown), and with end stops 12, the shoe having at, or adjacent

to, the back a reinforcing plate 13, suitably anchored to the shoe, the body being provided with a plurality of slots 14 extending from the wearing face substantially to the 5 reinforcing plate 13. To prevent the straightening out of the shoe during handling or transportation, as before referred to, we tie or bond the lower free ends of the segments or sections constituting the body 10, utilizing such means for so doing as may be readily anchored in the wearing face of the shoe during the process of casting, and which will readily wear away when the shoe is put into service. These tying or bonding 15 means may assume many and varied forms. For instance, in Figs. 1, 2 and 3, we have shown, as molded into the face of the shoe, expanded metal or wire mesh 15 extending practically across the entire wearing face of the shoe and bridging the slots or recesses 20 14, thus tying or bonding the several sections or segments of the body together, and prevent their separation which would otherwise happen, due to the slotting of the body 25 and when the shoe is straightened out in handling or transportation. Instead, however, of employing wire mesh or expanded metal, or like material, a tie or bond may be utilized for securing or holding in place 30 the adjacent sections or segments, and wherein such tie or bond extends but part-way across the sections instead of entirely across, as in the case of expanded metal. For instance, in Figs. 4, 5 and 6, we have 35 illustrated a tie which extends across the slot or groove 14, the tie comprising a bar or body 16 with enlarged ends 17, these enlarged ends affording a safe and secure anchorage in the body metal, this tie being 40 buried in the body of the shoe during the process of casting, the lower surface or side thereof preferably lying flush with the wearing face or surface of the shoe. Again, as illustrated in Figs. 7, 8 and 9, we have de- 45 signed a tie or bond somewhat in the form of a staple, this staple comprising a flat side 18, to bridge the recesses or grooves 14, and with two sides 19 bent at substantially right angles to the side 18, these sides 19 being each provided with a hole or opening 20 to 50 permit of the cast metal of the body of the shoe to flow through the same and anchor the device therein. In all of these instances, however, it will be noted that the means for securing the segments together, or at least 55 for holding the segments in their proper relative positions, and preventing the shoe from straightening out, are made separate from, but firmly attached or anchored to, the metal constituting the segments or body of 60 the shoe, and that while we have illustrated these several forms of the device for accomplishing the objects of the invention, yet such may assume a variety of forms, and therefore do not constitute in any wise a 65 limitation of the invention, the gist thereof lying in the employment of means made separate from the cast metal of the body of the shoe, and embedded, anchored, or otherwise firmly secured in the wearing face of 70 the shoe in such a way that the segments or sections thereof may be prevented from separating to such an extent as will permit the cracking of the shoe and the bending of the reinforcing plate embedded in the back 75 of the shoe.

What we claim is:—

A brake shoe comprising a cast metal body with a reinforcing back, said body provided throughout its length with spaced 80 transverse grooves dividing the body into a plurality of spaced segments, ductile members embedded in the wearing face of said segments, bridging said grooves and bonding said segments together. 85

Signed at New York, borough of Manhattan, county of New York and State of New York, this 20th day of October, 1914.

JOSEPH D. GALLAGHER.
GEORGE COOK.
